UNITED STATES PATENT OFFICE.

DAVID WEAR MCELROY, OF KAUFMAN, TEXAS, ASSIGNOR OF ONE-HALF TO GUY E. BOGGS, OF KAUFMAN, TEXAS.

WATER HEAD FOR DRILLING RIGS.

Application filed June 14, 1926. Serial No. 116,052.

This invention relates to a water head for drilling rigs, one of the objects being to provide a structure providing an extensive packing base whereby considerable saving of time is effected inasmuch as one packing can be used for a much longer period than packings generally employed in structures of this character.

A further object is to provide the structure with anti-friction bearings for the purpose of relieving pressure and allowing the shell of the structure to rotate much more freely than heretofore upon the stationary wash barrel.

A still further object is to provide means whereby wear upon the parts can be taken up readily, accidental displacement of the parts is prevented and the entire device held together properly under working conditions.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings, the preferred form of the invention has been shown. In said drawings,

Figure 1 is a central longitudinal section through the device.

Figure 2 is a section on line 2—2, Figure 1. Figure 3 is a section on line 3—3, Figure 1.

Referring to the figures by characters of reference 1 designates the stationary wash barrel having a threaded upper end as indicated at 2 for connection with a hose whereby water can be directed therein. This barrel extends into a shell 3 the upper portion of which is interiorly screw threaded as shown at 4. The lower portion of the shell is reduced in diameter as indicated at 5 and is interiorly screw threaded as shown at 6. Integral with this shell is an interior annular shoulder 7 the lower face of which is inclined as shown at 8. An annular enlargement 9 is provided on the barrel 1 within the shell 3 and arranged above and below this enlargement are roller bearings 10 which provide anti-friction means for holding the shell centered upon the barrel and freely rotatable relative thereto. The bear-

ings are held properly assembled with the barrel and with the shell by a hollow nut 11 which is fitted snugly about the barrel and is screwed into the shell so as to engage the threaded portion 4. This nut is engaged by a lock nut 12 adapted to jam against the end of the shell 3 as shown. The nuts 11 and 12 may be provided with recesses 13 whereby they can be engaged and actuated by a spanner wrench. The space within the shell 3 between flange 7 and the closed end of the nut 11 constitutes a lubricating chamber 14 for holding oil or grease and for use in emergencies there is provided a grease cup 15 which opens into this chamber as shown. 70

The tubular pin 16 has a threaded portion 17 which engages the interior thread 6 of the shell 3 and has its housed end flared as shown at 18. Packing indicated at 19 is arranged about the barrel 1 between the inclined face of the partition or flange 7 and the flared end 18 of the pin 16 so as to be properly compressed. A lock nut 19 engages the threaded portion of this pin and is adapted to jam against the lower end of the shell 3 this nut being preferably provided with recesses 20 whereby it can be engaged and actuated by a spanner wrench. Recesses are also provided in the pin 16 as shown at 21 by means of which a spanner wrench can be used for rotating the pin relative to the shell. 85

It is to be understood that the device constituting the present invention is not to be used on deep well drills but is to be used in connection with core drills and pin 16 and shell 3 rotate with the drill stem. The weight of the drill stem is never supported by the head constituting the present invention while the drilling operation is going on and the only centering means necessary is the barrel 1 which is stationary. 90

By providing the lock nut it will be apparent that all of the working parts of the head are kept in proper positions during the drilling operation, it being designated to have the threads so shaped that the lock nuts will tend to tighten automatically while the drilling operation is going on. Importance is attached to the use of the extensive packing at 19 which allows for a much longer run of the device without changing the packing than has heretofore been possible. Consequently there is a saving of much time and labor and the cost of oper- 110

ation is correspondingly reduced. In fact by this arrangement it has been found in practice that one packing will be sufficient for several months whereas heretofore frequent 5 changes of the packing has been necessary. The large lubricating chamber 14 permits the use of a considerable amount of lubricant so that after this chamber has once been filled very little attention need be given to 10 the lubrication of the parts.

What is claimed is:

15 A water head for attachment to and adapted to be supported by a core drill, said head including a stationary water barrel having an annular enlargement between its ends, a shell housing a portion of the barrel and having an enlarged end portion and a reduced end portion, a hollow nut fitted snugly about the barrel and threaded into 20 the enlarged end portion of the shell, said nut being spaced for the greater portion of its length from the barrel, the nut and

enlarged portion cooperating to provide a lubricant compartment, spaced annular series of tapered roller bearings interposed between the annular enlargement on the barrel and the nut and between the annular enlargement and the inner end of the enlarged portion of the shell, said bearings constituting means for taking up end and side thrust and 25 for holding the barrel against longitudinal movement relative to the shell and in position at all times concentric with the shell, a packing between the reduced portion of the shell and the barrel, and adjustable means 30 engaging the reduced portion of the shell for compressing the packing about the barrel, said adjustable means constituting means for engaging a core drill to support the water head thereon. 35

40 In testimony that I claim the foregoing as my own, I have hereto affixed my signature.

DAVID WEAR McELROY.
